UNITED STATES PATENT OFFICE.

REME A. BEAUSEJOUR AND GUSTAV DRUBEL, OF NEW YORK, N. Y., ASSIGNEES TO STANDARD VARNISH WORKS, OF NEW YORK, N. Y., A CORPORATION OF NEW YORK.

LIQUID-COATING MACHINE.

No. 929,375.

Specification of Letters Patent.

Patented July 27, 1909.

Application filed February 18, 1908. Serial No. 416,486.

To all whom it may concern:

Be it known that we, REME A. BEAUSEJOUR, a subject of the Crown of Great Britain, and resident of the borough of Brooklyn, in the city and State of New York, and GUSTAV DRUBEL, a citizen of the United States, and resident of the borough of Richmond, in the city and State of New York, have invented a new and useful Improvement in 10 Liquid-Coating Machines, of which the following is a specification.

This invention relates to that type of liquid coating machines in which the articles to be treated to a liquid coating are raised and lowered by fluid actuated means, the parts being so constructed, arranged and operated that the articles being treated are coated uniformly and in which the articles are so held that the liquid dripping therefrom will 20 be prevented from accumulating on any surface of the articles.

A practical embodiment of our invention is represented in the accompanying drawings in which—

25 Figure 1 represents in side elevation partially in section, an embodiment of our invention as applied to a single dipping tank, the parts being shown in their lowered positions in full lines and in their raised positions in dotted lines. Fig. 2 is a top plan view of the same, Figs. 3, 4 are enlarged detail front and side views partially in section, of the means for engaging and supporting the upper portions of the articles being treated, 30 Figs. 5, 6, 7, are detail side, end and top plan views of the means for carrying the article holder, Fig. 8 is a view in end elevation, partially in section, the parts being shown in their lowered position, Figs. 9, 10, 11, are respectively detail views in top plan, vertical central section and inverted plan, of the slide and the swinging bracket for carrying the article holder, Figs. 12, 13, are detail views in vertical longitudinal central section 35 and end elevation, of the means for locking the holder carrying bracket in its operative position over the dipping tank, Fig. 14 is a detail view in side elevation, of a modified form of machine in which the apparatus is 40 constructed for utilizing two dipping tanks and two article holders, the parts being shown in full lines in their lowered positions and in dotted lines in their raised positions. 45 Fig. 15 is a top plan view of the same, the holders and their double supporting bracket

being shown in full lines over the dipping tanks and in dotted lines swung into position for facilitating the insertion and removal of the article holders, and Fig. 16 is a detail sectional view showing the means for attaching the flexible connection of the counterbalance device to the center of the double holder carrying bracket.

Proceeding to describe the form shown in Figs. 1 to 13 inclusive, the dipping tank is denoted by 1 and is herein shown as provided with a floor or other support 2 at its bottom and a platform 3 near its top. The cylinder 4 of a fluid actuated device is located adjacent to the tank 1. A piston 5 is fitted to reciprocate within the cylinder 4 and its rod 6 extends upwardly through the top of the cylinder. The fluid inlet pipe is denoted by 7 and has a pressure regulator 8 and a pressure gage 9 therein. This inlet pipe 7 is provided with a branch pipe 10 leading to the top of the cylinder 4 and a branch pipe 11 leading to the bottom of the said cylinder. The fluid outlet pipe 12 is connected to the branch pipe 10 through a pipe 13 having a manually operated valve 14 therein. This outlet pipe 12 is also connected to the inlet branch pipe 11 through a pipe 15 having a manually operated valve 16 therein. A manually operated valve 17 is located in the branch inlet pipe 11 and a manually operated valve 18 is located in the inlet pipe 7.

A horizontally swinging bracket is carried by the piston rod 6 above the cylinder 4, which bracket comprises a tubular post 19 surrounding the piston rod 6, which tubular post has a horizontal arm 20 projecting from its lower end, and diagonally arranged supporting straps 21 extending from its upper end to the horizontal arm 20 at different points between its outer and inner ends.

A vertical post 22 is arranged adjacent to the cylinder 4, which post is of sufficient height to extend above the top of the bracket when the bracket is in its raised position. A pulley 23 is mounted at the top of the post 22, over which pulley runs the flexible connection 24 of a bracket counter-balancing device, one end of which flexible connection is attached to the horizontal arm 20 of the bracket and the other end of which connection is attached to the counterbalance weight 25.

To insure an even vertical sliding movement of the bracket we provide a guide com-

prising a tubular post 26 which surrounds the vertical post 22, and a tubular post 27 which surrounds the tubular post 19 of the bracket. To insure an even frictional engagement of the tubular post 26 with the post 22, and to reduce friction, the tubular post 26 is provided with upper and lower bushings 28, 29.

To properly counterbalance the bracket by the weight 25 so as to reduce the side strain on the vertical post 22 to a minimum, the upper end of the tubular post 19 of the bracket is provided with a laterally extended arm 30, over the end of which the flexible connection 24 passes.

15 The horizontal arm 20 of the bracket is provided with a spring-actuated pin 31 which is fitted to enter a socket 32 in the tubular post 27 of the bracket guide when the article holder is suspended in position from the bracket and when the bracket is in its proper position over the dipping tank. The spring 33 of this pin 31 tends to hold the pin released from the socket 32.

20 A carriage 34 is fitted to reciprocate along the horizontal arm 20 of the holder carrying bracket. The article holder comprises a skeleton frame having vertical side bars 35 and diagonal side bars 36 connecting the top 37 and bottom 38 of the holder. The top 37 of the holder is provided with a plate 39 having a plurality of holes 40 arranged in a horizontal line along the plate. The carriage 34 is provided with a depending arm 41 and a pin 42 is arranged to pass through the said 25 depending arm and one of the holes 40 in the plate 39 for suspending the article holder from the carriage. The top of the holder is further provided with a strap 43 which is bent to form a recess for a yielding stop 44 carried by the horizontal arm 20 of the swinging bracket. In the present instance this yielding stop 44 has a spring 45 for yieldingly holding it at the limit of its downward movement in the path of the strap 43 of the holder. 30 When the yielding stop 44 is within its socket, the holder is yieldingly held in position to be lowered into or raised from the tank.

35 A spring pressed latch 46 is hinged at 47 to a projection 48 on the horizontal arm 30 of the bracket, which latch is provided with a vertical series of notches 49 arranged to receive in one of them a tooth 50 on the top of the holder, according to the inclination which 40 the holder assumes under the influence of the weight of the articles to be dipped. The lower end of the spring pressed latch 46 is provided with a cam 51, which is arranged in position to be engaged by the pin 52 carried 45 by the top of the holder, whereby the said latch is removed from its engagement with the holder when it is desired to remove the holder from its position over the tank.

50 The holder itself is shown herein as particularly well adapted for use in holding the

several parts of a piano. The bottom 38 of the holder is provided with a plurality of laterally extended cross bars 53 forming supports for the bottoms of the articles. A cross-bar 54 extends between the side bars 36 of the holder a short distance above the bottom 38, which cross-bar is provided with a plurality of laterally adjustable clamps 55 which are so arranged that they may clamp the heavier articles to the holder. The top 37 of the holder is provided with a plurality of loop frames 56 which are pivotally clamped to the top 37 in any desired angular position with respect thereto, by suitable fastening devices, such, for instance, as thumb nuts 57, engaging pivotal bolts 58, which pass through the sides of the said top 37 of the holder. Each one of these loop frames 56 is provided with a series of spring-pressed fingers 59 having pointed ends arranged to engage the tops of the articles to be dipped, the said fingers having a sliding movement in the horizontal portion of the loop frame 56. A withdrawing cam 60 is pivoted at 61 on each of the spring pressed fingers 59 in position to engage the lower horizontal portion of the loop frame 56 against the tension of the spring 62 which tends to hold the finger at the limit of its downward movement. When the withdrawing cam is in one position, the finger will be yieldingly held against the article and when in its other position, the finger will be withdrawn from engagement with the article.

55 The positions of the several article holding devices are such that the articles are held so that when the liquid is dropping therefrom it will run along an edge to a corner and drop from said corner, thus eliminating entirely the streaking of the same on the surfaces of the article, which has heretofore been so undesirable a feature in dipping machines.

60 The spring-pressed pin 31 is forced into its socket 32 against the tension of its spring 33 when the carriage 34 is moved into its position over the tank, by the following means. The carriage 34 is provided with an inwardly extended push bar 63 arranged to engage the sliding pin 64 in alignment with the locking pin 31, a yielding connection between the two pins being formed by a coiled spring 65 so that if the pin 64 should be pressed in when the bracket is not in position over the tank, the spring 65 would yield sufficiently to prevent breakage of the parts. When the bracket is swung into a position over the tank, the pin 31 would enter the socket 32 in the tubular post 27 of the guide under pressure exerted by the said spring 65.

65 In operation, presupposing the fluid to have been admitted to the under side of the piston 5 and permitted to escape from the upper side thereof for causing the piston rod and the bracket hinged thereon to be raised to the limit of its upward movement; the

bracket is swung horizontally into the desired position for the placing of the articles in the holder, the holder and its supporting carriage being moved out to the end of the bracket. After the articles have been carefully secured in position within the holder, the bracket is swung around into position over the tank. The carriage and the holder suspended therefrom are then moved inwardly along the horizontal arm 20 of the bracket until the yielding stop 44 drops into the socket in the strap 43 on the holder, thus positioning the holder over the tank. The weight of the articles within the holder will cause the holder to seek its center of gravity on the bolt 42 and as the holder is moved into its position over the tank, the spring pressed latch 46 will be permitted to lock the holder in this position because of the engagement of one of its notches 49 with the tooth 50 on the top of the holder. This inward movement of the carriage and holder will also force the pin 31 into its socket 32 in the bracket guide for locking the bracket against a swinging movement while the article is being dipped. The fluid is now admitted to the top of the piston 5 and permitted to escape from the bottom thereof, thus forcing the bracket and the holder carried thereby, downwardly for immersing the articles in the liquid in the tank. It will be seen that the spring pressed latch 46 because of its engagement with the holder, will prevent any movement of the holder owing to the tendency of the articles being dipped to float when immersed in the tank. When it is desired to raise the articles from the tank, the fluid is admitted to the under side of the piston 5 and permitted to escape from the upper side thereof, thus causing the piston rod and the bracket hinged thereon to slowly rise and with them the article holder. The guide for the bracket in conjunction with the counterbalancing of the weights insures an even vertical movement of the parts, thereby producing a superior finish to the articles. After the articles have been raised from the tank and at the proper time the carriage and holder may be moved outwardly along the horizontal arm of the bracket and the bracket may then be swung into any desired horizontal position for facilitating the removal of the articles.

In Figs. 14, 15 and 16, we have shown a modified form arranged for supporting a double bracket, the horizontal arms of which extend in opposite directions from the guide. In this form the end of the flexible connection of the counterbalance device is secured to a swivel block 66 mounted in the top of the piston rod 6.

It is evident that various changes might be resorted to in the construction, form and arrangement of the several parts without departing from the scope and spirit of our

invention; hence we do not wish to limit ourselves strictly to the form herein shown, but

What we claim is:

1. In a machine of the character described, a dipping tank, a horizontally swinging bracket, an article holder carried thereby, means under the control of the article holder for locking the bracket in position over the tank and means for raising and lowering the bracket.

2. In a machine of the character described, a dipping tank, a horizontally swinging bracket, an article holder carried thereby, means under the control of the article holder for locking the bracket in position over the tank and fluid operated means for raising and lowering the bracket.

3. In a machine of the character described, a dipping tank, a horizontally swinging bracket, a carriage fitted to reciprocate thereon, an article holder suspended from the carriage, means controlled by the carriage for locking the bracket in position over the tank and means for raising and lowering the bracket.

4. In a machine of the character described, a dipping tank, a horizontally swinging bracket, a carriage fitted to reciprocate thereon, an article holder suspended from the carriage, means controlled by the carriage for locking the bracket in position over the tank and fluid operated means for raising and lowering the bracket.

5. In a machine of the character described, a dipping tank, a horizontally swinging article supporting bracket, means for counterbalancing the bracket and fluid operated means for raising and lowering the bracket.

6. In a machine of the character described, a dipping tank, a horizontally swinging article supporting bracket, means for counterbalancing the bracket, fluid operated means for raising and lowering the bracket and a guide for insuring an even movement of the bracket.

7. In a machine of the character described, a dipping tank, an article supporting bracket, means for raising and lowering the bracket and a guide for insuring an even movement of the bracket comprising a vertical post, and a tubular post carried by the bracket and surrounding said vertical post.

8. In a machine of the character described, a dipping tank, an article supporting bracket, fluid operated means for raising and lowering the bracket and a guide for insuring an even movement of the bracket comprising a vertical post and a tubular post carried by the bracket and surrounding said vertical post.

9. In a machine of the character described, a dipping tank, a horizontally swinging article supporting bracket, means for raising and lowering the bracket and a guide for in-

suring the even movement of the bracket comprising a vertical post, and a pair of connected tubular posts, one surrounding said vertical post and the other surrounding a portion of the bracket.

10. In a machine of the character described, a dipping tank, a horizontally swinging article supporting bracket, fluid operated means for raising and lowering the bracket and a guide for insuring the even movement of the bracket comprising a vertical post, and a pair of connected tubular posts, one surrounding said vertical post and the other surrounding a portion of the bracket.

11. In a machine of the character described, a dipping tank, an article supporting bracket, means for raising and lowering the bracket, means for suspending an article from the bracket and means for locking the article in its suspended position against a change in its position due to the flotation effect of the liquid during the dipping operation.

12. In a machine of the character described, a dipping tank, an article supporting bracket, fluid operated means for raising and lowering the bracket, means for suspending an article from the bracket and means for locking the article in its suspended position against a change in its position due to the flotation effect of the liquid during the dipping operation.

13. In a machine of the character described, a dipping tank, an article supporting bracket, means for raising and lowering the bracket, an article holder pivotally suspended from the bracket and means for locking the article holder in its suspended position against a change in its position due to the flotation

effect of the liquid upon the article during the dipping operation.

14. In a machine of the character described, a dipping tank, an article supporting bracket, fluid operated means for raising and lowering the bracket, an article holder pivotally suspended from the bracket and means for locking the article holder in its suspended position against a change in its position due to the flotation effect of the liquid upon the article during the dipping operation.

15. In a machine of the character described, a dipping tank, an article supporting bracket, means for raising and lowering the bracket, a carriage fitted to reciprocate along the bracket, an article holder pivotally suspended from the carriage and means carried by the bracket for locking the holder in its suspended position against a change in its position due to the flotation effect of the liquid upon the article during the dipping operation.

16. In a machine of the character described, a dipping tank, an article supporting bracket, means for raising and lowering the bracket, a carriage fitted to reciprocate along the bracket, an article holder suspended from the carriage and means for yieldingly holding the holder in position over the tank.

In testimony, that we claim the foregoing as our invention, we have signed our names in presence of two witnesses, this fourteenth day of February 1908.

REME A. BEAUSEJOUR.
GUSTAV DRUBEL.
